UNITED STATES PATENT OFFICE.

JOHN E. MOORE, OF WHITING, INDIANA, ASSIGNOR TO STANDARD OIL COMPANY, OF WHITING, INDIANA, A CORPORATION OF INDIANA.

BREATHER BAG.

Application filed May 13, 1927. Serial No. 191,153.

This invention relates to improvements in breather bags.

In application Serial No. 702,029, filed March 26, 1924, by Robert E. Wilson and Serial No. 180,317, filed April 1, 1927, by Robert E. Wilson and others, breather bags have been described in which the breather bag is provided with a superimposed weight which is counterpoised to a varying extent 10 depending upon the degree of inflation of the bag.

The present invention relates more particularly to an improved form of varying counterpoise.

The invention will be more readily understood from the following description in conjunction with the drawings, in which:

Figure 1 is an elevation, partly in section, illustrating one form of the invention; and Fig. 2 is a similar view of a modified form of the invention.

Referring to the embodiment shown in Fig. 1, 10 is a breather bag which carries a superimposed weight 11 which is partly supported by cords 12, preferably four in number. The cords 12 are attached at 13 to a counterpoise belt 14. The belt 14 is wholly or partly in the form of a broad belt of leather or webbing or other suitable flexible material. It carries weights 15, which are preferably blocks of lead, said weights being distributed with respect to the point of attachment 13 and the position of the breather bag 10 so as to enable substantially 30 constant pressure to be maintained in said bag. As indicated in the applications referred to, it is intended that the constant pressure maintained in breather bag 10 should be of a magnitude to establish substantially 40 atmospheric pressure in the vapor space of the tanks to which the breather bag is connected.

The belt 14 is continuous and is mounted on pulleys 16, said pulleys being provided with flanges 17 for the purpose of preventing displacement of the belt 14 therefrom. The weights 15 are of such magnitude and are located in such spaced relation with reference to the particular bag with which the

counterpoise is to be used, that substantially 50 uniform pressure is maintained upon the bag 10 in all degrees of inflation. The specific location of the weights 15 must be determined by actual experiment with the particular installation. In general, it has 55 been found that with a breather bag of the type illustrated, which is supported around its equator, the weights 15 should exert a substantially constant counterpoising effect upon the superimposed weight 11 between 60 the positions corresponding to full inflation and about one-third inflation of the bag, and exert a gradually decreasing counterpoising effect as the bag deflates from one-third full to empty. 65

The operation is as follows: Assuming the bag to be substantially fully inflated and that it is becoming deflated due to withdrawal of liquid from the tank to which it is connected or due to fall of temperature 70 or other causes, the weights 15 are now located near the lower portion of the left hand vertical side of the belt 14. As the bag deflates the weights 15 ascend, exerting a constant counterpoising effect on the 75 weight 11 until a certain degree of deflation is obtained at which it is necessary for the counterpoising effect to decrease in order to maintain substantially uniform pressure 80 in the vapor space of the storage system or tank. As indicated above, this degree of deflation is approximately two-thirds for the type of bag illustrated. As deflation continues beyond this point, some of the weights 15 pass to the upper side of the 85 upper pulley 16, no longer exerting a counterpoising effect on the weight 11. When the deflation of the bag proceeds further, some of the weights 15 will proceed to the right-hand side of the pulleys 16 and 90 there exert a force which partly counterbalances the effect of some of the counterpoising weights 15 on the left-hand side. As will readily be understood, by calibrating the bag in the first instance, it is possible 95 to arrange the weights 15 so that constant pressure is maintained in the bag 10 in all stages of inflation and deflation.

Referring to the modified form shown in Fig. 2, the bag is designated 10', the superimposed weight 11', the cords therefor 12', the belt 14', the point of attachment of the 5 cords 12' thereto 13'. The lead weights carried by the belt 14' are designated 15'.

In this form, also, the belt 14' is continuous and is preferably supported by rollers so that the path of the weights 15' is substantially 10 in the shape of an inverted L. The belt 14' may be maintained in this position by pulleys 16' preferably provided with flanges 17' and by rollers 18 arranged to provide an arcuate path 19 and a horizontal 15 supporting path 20. The rollers 18 are preferably provided with rims 21 for the purpose of preventing the belt from slipping therefrom. The rollers 18 may suitably be mounted upon a frame 22 suitably 20 carried by the building in which the bag is housed.

The operation is similar to that of the form shown in Fig. 1. The calibrating and arrangements of the weights 15' will be somewhat 25 different on account of the fact that after passing upwardly over the arcuate part of the path 19, the weights proceed to the horizontal path 20 where they exert no force on either the bag or active portion 30 of the counterpoise.

Although the present invention has been described in connection with the details of specific embodiments thereof, it is not intended that such details shall be regarded 35 as limitations upon the scope of the invention except in so far as included in the accompanying claims.

I claim:

1. In combination, a breather bag, a superimposed weight, a varying counterpoise for 40 said weight connected thereto, said counterpoise comprising a continuous member mounted so as to be moved in conjunction with said superimposed weight, and weight members mounted on said continuous member and adapted to exercise a varying counterpoising effect upon said superimposed weight.

2. In combination, a breather bag, a superimposed weight thereon, a continuous belt 50 mounted on rotatable elements, means attaching said superimposed weight to said belt to effect simultaneous movements thereof, and weights attached at spaced intervals to 55 said belt for the purpose of exercising a variable counterpoising effect on said superimposed weight in accordance with its position.

3. In combination, a breather bag, a superimposed weight, a continuous belt mounted 60 on rotatable members, weights mounted on said belt over a part thereof, flexible means connecting said superimposed weight to said belt in such a manner that said weights 65 exert a substantial counterpoising effect

upon said superimposed weight when the latter is in an elevated position, said weights being adapted to be moved progressively into a position to reduce said counterpoising effect as the superimposed weight descends. 70

4. In combination, a breather bag, a superimposed weight thereon, a continuous belt, a series of weights mounted on said belt, rotatable means for defining a vertical and horizontal path for said belt, a series of 75 weights on said belt and flexible means connecting said superimposed weight and said belt, so that in the elevated position of the superimposed weight, a substantial number of said weights of the belt are in a vertical 80 position and exercising a substantial counterpoising effect on said superimposed weight and said weights move into the horizontal position of the belt as the superimposed weight descends. 85

5. In combination, a breather bag, a superimposed weight thereon, a continuous belt mounted on rotatable elements, and having vertical upwardly and downwardly directed flights, means attaching said superimposed 90 weight to said belt to effect simultaneous movements thereof, and weights attached at spaced intervals to said belt for the purpose of exercising a variable counterpoising effect 95 on said superimposed weight in accordance with its position.

6. In combination, a breather bag, a superimposed weight, a continuous belt mounted on rotatable members and having vertical upwardly and downwardly directed flights, 100 weights mounted on said belt over a part thereof, flexible means connecting said superimposed weight to said belt in such a manner that said weights exert a substantial counterpoising effect upon said superimposed 105 weight when the latter is in an elevated position, said weights being adapted to be moved progressively into a position to reduce said counterpoising effect as the superimposed weight descends. 110

7. In combination, a breather bag, a superimposed weight, a varying counterpoise for said weight connected thereto, said counterpoise comprising a continuous member mounted so as to be moved in conjunction 115 with said superimposed weight, and weight members mounted on said continuous member in such a manner as to exercise a uniform counterpoising effect on said superimposed weight for a substantial part of the deflation period and to exercise a gradually decreasing counterpoising effect thereon during the last stage of deflation.

8. In combination, a breather bag, a superimposed weight, a varying counterpoise for 120 said weight connected thereto, said counterpoise comprising a continuous belt mounted on rotatable members and connected to said superimposed weight so as to be moved in conjunction therewith, weights mounted on 125

said belt, said belt having a vertical flight so that weights thereon exercise a counterpoising effect on said superimposed weight, and another flight in which weights thereon do not exercise a counterpoising effect on said superimposed weight, said weights being so arranged on said belt that they exert a substantially constant counterpoising effect when the bag is approximately one-third or more inflated and a gradually decreasing counterpoising effect as the bag deflates from approximately one-third inflated to empty condition.

JOHN E. MOORE.
